UNITED STATES PATENT OFFICE.

WILLIAM FREEGARD, OF ST. LOUIS, MISSOURI, ASSIGNOR TO THE BARBER ASPHALT COMPANY, OF PHILADELPHIA, PENNSYLVANIA, A CORPORATION OF WEST VIRGINIA.

ROOF COVERING.

Application filed February 24, 1923. Serial No. 620,873.

To all whom it may concern:

Be it known that I, WILLIAM FREEGARD, a citizen of the United States, residing at St. Louis, county of St. Louis, and State of Missouri, have invented certain new and useful Improvements in Roof Coverings, of which the following is a specification, reference being had to the accompanying drawings.

- 10 This invention relates to roofing materials, and the object is to provide a shingle strip and method of making the same which consists in severing a strip of flexible material longitudinally along a deviating or zigzag path to form two shingle strips having indented edges forming point-down shingle ends, and forming each shingle end with an enlargement which is subsequently bent under to form a locking tab.
- 20 These and other objects are accomplished by what I now regard, from among other possible forms and arrangements, as the preferred embodiment of my invention, to be hereinafter described, illustrated in the accompanying drawings and particularly pointed out by the appended claims.

In the drawings, Figure I is a view in plan of a strip of roofing material illustrating the manner in which it is severed longitudinally to form two shingle strips.

Figure II is a view in plan of a portion of a shingle strip with formed shingle ends and showing the latter folded under to constitute locking tabs.

35 Figure III is a view in top plan of a number of shingle strips, constructed in accordance with my invention, and illustrating the manner in which superposed strips are interlocked while simulating point-down shingles; and,

Figure IV is a view in section taken on the line IV—IV of Figure III.

Considering first the preferred method by which my improved shingle strip is manufactured reference is had to Figures I and II wherein 10 indicates a strip of web roofing material such as bitumen impregnated felt, paper, or other fibrous material, usually surface coated with granular or silicious material such as slate, silica, or the like, to form a hard wear and weather resistant surface.

The strip 10 is severed longitudinally; and this may be accomplished continuously as the web material is delivered from a roll

and fed through a suitably constructed machine for this purpose.

The web is severed along a deviating or zigzag path, centrally, to form two shingle strips 11 and 12, as a result of which the severed edges of the strips are formed with point-down shingle ends 13 having converging side edges terminating in shingle points, so that when the strips are overlaid in applying the strips to a roof the effect is that of diagonally laid shingles.

Each shingle end 13 is formed, during the process of splitting the web, with a tip enlargement 14, preferably of the configuration shown, comprising a straight edge 15 and tapering side edges 16 which extend in the general direction of the side edges of the shingle ends but at a slightly different angle. The lines of incision, when forming the side edges of the shingle ends, are continued into the tip enlargements 14, as indicated at 17, to define auxiliary locking members 18 which are thus partly severed from said enlargements 14. It will be noted that in forming the tip enlargements 14 complementary shaped recesses 19 are formed between adjacent shingle ends 13 of each strip 11 or 12, the formation of the auxiliary locking members 18 resulting in the provision of opposed shoulders 20 in the recesses 19.

The shingle strips 11, 12 are finished by folding under the tip enlargements 14 along a line connecting the ends of the incisions 17, the line of folding being indicated by 20 dotting in Figure II. The folding of the tip enlargements 14 may be accomplished by special machinery designed for the purpose; and if desired the folding mechanism may be embodied in the web splitting machine. In thus folding the tip enlargements 14 the latter form locking tabs; and it will be noted that the auxiliary locking members 18 will remain unfolded and will project beyond the edges of the shingle ends 13.

When laying my improved shingle strips in the manner shown in Figures III and IV the tip enlargements or locking tabs 14 of overlying strips are inserted through the recesses 19 of underlying strips, said locking tabs thus securely gripping the edges of the underlying strips and the auxiliary locking members 18 engaging the underside of said strips to enhance the locking effect. 110

The shoulders 20 function to prevent accidental separation of two adjacent strips if the shingle ends 13 are raised or shifted relatively. Fastening members such as 5 nails are driven through the shingle strip into the roof preferably at points directly above the locking notches 19, the exact allocation of the nails being such that the tip enlargements of a succeeding strip may be 10 readily engaged in the notches. If desired additional nails may be employed in other portions of the strip providing that they be overlapped by the succeeding strip to preclude the possibility of water entering be- 15 tween the superposed layers.

While the roofing material of my invention lends itself readily to being formed into roll packages for shipment, it may obviously be cut to convenient lengths (say eight, ten 20 or twelve feet, which may be easily handled in laying) and stacked for flat packaging, suitable stiffening sheets of corrugated cardboard or its equivalent being incorporated in the package to protect the shingling 25 against flexure or damage in the course of its transportation.

Having thus described my invention, I claim:

1. A shingle strip of flexible water-proof 30 material having one longitudinal edge formed with alternating angular projections simulating point-down shingle ends and recesses of corresponding size and configuration, each of said angular projections 35 having an integral tip enlargement with converging incisions defining opposed lateral projections, and said tip enlargements being adapted to be folded under to constitute a locking tab.

2. A shingle strip of flexible water-proof 40 material one longitudinal edge whereof is severed to define alternating projections simulating point-down shingle ends and recesses of right angled configuration and 45 corresponding size, each of said projections having an integral tip enlargement with converging incisions defining opposed lateral projections, and said tip enlargement being capable of folding upon itself to con- 50 stitute a locking tab.

3. A shingle strip of flexible water-proof 55 material having a longitudinal edge severed to provide angular projections simulating point-down shingle ends and recesses of corresponding size and configuration, each of said projections having an integral en-

largement with opposed lateral projections partly severed whereby said enlargement may be folded under to form a locking tab leaving the projections divergently unfolded to constitute auxiliary locking members. 60

4. A shingle strip of flexible water-proof material having one edge deviatingly severed to simulate point-down shingle ends 65 with mutually configured alternating recesses, each said shingle point having an integral enlargement with converging incisions and being adapted for retroversion to constitute a locking tab, said incisions defining locking ears that divergently project laterally beyond the shingle point edges when said point is underfolded. 70

5. A shingle strip of flexible water-proof material one longitudinal edge whereof is 75 severed to form substantially right angled point-down shingle points with mutually configured equal sized alternating recesses, each said shingle point having an integral enlargement with converging incisions and being adapted for underfolding to constitute 80 a locking tab, said incisions defining diverging members projecting laterally beyond the shingle point oblique edges. 85

6. As an article of manufacture, a strip 90 of flexible water-proof material having one edge deviatingly severed to simulate point-down shingle ends with mutually configured recesses between each pair of adjacent shingle ends, and an integral enlargement 95 with converging incisions at the tip of each shingle end, said shingle ends when folded under constituting locking tabs adapted to enter the recesses of an underlying corresponding strip of said material. 95

7. A water-proof covering comprising a plurality of flexible material strips, each having one longitudinal edge severed to simulate substantially right-angled point-down shingle points with correspondingly 100 configured recesses alternating between each pair of said adjacent points, and an enlargement formed integrally with each point having converging incisions, said point when folded under constituting a locking tab with 105 lateral divergently directed projections defined by the aforesaid converging incisions.

In testimony whereof, I have hereunto signed my name at Madison, Illinois, this thirteenth day of February, 1923.

WILLIAM FREEGARD.
